UNITED STATES PATENT OFFICE.

WILLIAM N. RUMELY, OF LA PORTE, INDIANA.

TRACTION-ENGINE.

SPECIFICATION forming part of Letters Patent No. 284,676, dated September 11, 1883.

Application filed December 22, 1882. (No model.)

To all whom it may concern:

Be it known that I, WILLIAM N. RUMELY, a citizen of the United States, residing at La Porte, in the county of La Porte and State of Indiana, have invented a new and useful Improvement in Traction-Engines, of which the following is a specification.

My invention relates to the running-gear of a traction-engine; and the object of my invention is to provide a simple, substantial, and efficient device for cushioning the rear or fire-box end of the boiler upon the rear axle.

Figure 1 is a rear end view of a traction-engine provided with my improvements. Fig. 15 2 is a side view of the same engine; and Fig. 3 is a top view of a portion of the rear axle and of a horizontal section, along the line xy , of the fire-box sheet and of the spring-case.

In the figures, A indicates the rear axle, on 20 which the traction-wheels rotate. S indicates the helical steel springs, which support the boiler; C, the spring-case and axle-guides; c, conical lugs which keep the springs in central position, and s indicates a wrought-iron strap. 25 W is the gear-wheel, which is attached to the traction-wheel, and which is driven by the pinion P on the differential-gear shaft. The latter runs in bearings, which are supported by the front head of the fire-box.

30 In traction and similar engines it is desirable to relieve the boiler and all the machinery attached thereto from shocks caused by jostling when engines are driven over rough roads and railway-crossings, and the like. In order to 35 cushion the boiler upon the rear axle, or the axle of the traction-wheels, I have made use of an axle which is bent under the boiler and is continuous, and therefore independent of the boiler. I then cushion the rear end of the 40 boiler upon this axle by means of the helical steel springs S. To each side of the boiler there is bolted a cast-iron spring-case, C, in which the spring S is incased, and which has a solid top, t, that rests upon the top of the 45 spring. The axle A has a lug, c, on its upper side, for keeping the bottom of the spring in position, and the solid top t of the spring-case also has a lug, c, for keeping the upper end of the spring in place. The sides of the 50 spring-case are continued down below the lower end of the spring along the sides of the axle, and form the guides for the latter, so that when

the boiler vibrates vertically upon the springs the portion of the axle adjacent to the boiler and upon which the springs rest will be free to 55 move within the spring-case. By means of these guides and the wrought-iron strap s, which is bolted to the bottom of the boiler, the axle is prevented from being deflected out of its proper position.

60 In Fig. 1 the spring-case is shown in section, in order to show the arrangement of the spring and axle within the case. The section is along the line mn of Figs. 2 and 3. For the same reason Fig. 3 is given, showing a portion of 65 the rear axle and the top view of a horizontal section, along the line xy of Figs. 1 and 2, of the spring-case and of the fire-box sheet.

It is evident that when the boiler of a traction-engine is supported upon springs, as in 70 this case, any weight added to or taken from the boiler would cause a corresponding variation in the compression of the springs. The vertical component of an opposing force due to a traction-wheel running against or over an 75 obstacle would cause a proportional variation in the compression of the spring next to that wheel. Similarly, were the traction-wheels to be suddenly stopped, when running forward, on account of striking some obstacle, and when 80 a uniform force was being applied through the driving mechanism by the steam, the pinion P would tend to run up on the gear-wheel W and to raise the boiler up, which would cause a proportional variation in the tension on the 85 springs. In running backward the pinion P would tend to run down around the gear-wheel W, and hence to increase the load upon the springs. The springs, then, and the power transmitted through the driving mechanism, 90 may act to produce the same or the opposite effect, and since they so act relatively to each other the springs will serve not only to prevent shocks from being transmitted to the boiler and its attached mechanism, but they 95 will serve the additional very useful function of cushioning the power, and hence of relieving the mechanism of sudden severe strains.

I am aware that continuous axles bent under the boiler, and similar to the one here shown 100 and described, have been used before, and also that helical springs have been used for supporting a boiler upon an axle; but I am not aware that such a construction as here shown,

described, and claimed has ever, before been known or used.

I claim—

1. The spring-case and axle-guide shown 5 and described, being a casting the base of which is substantially a plate capable of being bolted to the side of the boiler of a traction-engine, and having in common with itself two parallel outwardly-projecting vertical walls 10 and a third outwardly-projecting wall connecting the two former at or near their upper ends, so as to form a case open at the side and below for resting upon, holding, and guiding the helical spring which cushions the boiler 15 upon the axle, and for holding and guiding said axle while permitting vibrations of the spring, the top of the case being provided with a lug for retaining the top of the spring in position, and the parallel side walls of the case 20 extending below the top of the axle sufficiently to form suitable guides for the latter.

2. A spring-case and axle-guide consisting, essentially, of a base-plate capable of being bolted to the boiler, and having parallel outwardly-projecting vertical walls connected at 25 or near their upper ends by a similar cross-wall, the whole forming a case open at the side and below, in combination with a helical spring and a continuous axle bent under the boiler, 30 said axle having a construction adapting it to freedom of play between the parallel side walls of the case as guides to correspond with the

compression of the helical spring which rests upon the axle within the case, and is compressed by the top wall of the case, and said spring 35 being retained in position by a lug on the under side of said cross-wall and a lug or other similar suitable retaining device on the upper side of the axle.

3. A spring-case and axle-guide consisting, 40 essentially, of a base-plate capable of being bolted to the side of the boiler, and having parallel outwardly-projecting vertical walls connected at or near their upper ends by a similar cross-wall, the whole forming a case open 45 at the side and below, in combination with a helical spring and a continuous axle bent under the boiler, said axle having a construction adapting it to freedom of play between the parallel side walls of the case as guides to correspond with the compression of the helical spring which rests upon the axle within the case, and is compressed by the top wall of the case, and said spring being retained in position by a lug on the under side of said cross- 50 wall and a lug or other similar suitable retaining device on the upper side of the axle, and with a wrought-iron strap embracing the middle portion of the axle which it guides, and being bolted to the boiler.

WILLIAM N. RUMELY.
